LIQUID FILLING HEAD

DEDICATORY CLAUSE

The invention described herein may be manufactured, used, and licensed by or for the Government for governmental purposes without the payment to me of any royalty thereon.

My invention relates to an apparatus, system, and method for rapidly filling containers with liquid material which is highly toxic.

While filling devices have been disclosed in the prior art, these all presented certain disadvantages and problems. For example, the prior art devices required the container to have a strippable plastic coating to utilize the device; or the container required a decontamination washdown following filling due to overflow; or dripping or work surfaces became contaminated due to container overflow; or complicated weighing, volumetric measurement, and timing techniques were required to be employed in conjunction with the prior art filling device; or the container to be filled left the filling station in a partially or unfilled condition or containing a quantity of foam. My invention was conceived and reduced to practice to overcome and solve these disadvantages and problems.

A principal object of my invention is to provide a reliable apparatus system, and method for rapidly and completely filling containers with toxic liquid material and eliminating partially or unfilled containers from leaving the filling station.

Another object of my invention is to provide a reliable apparatus, system, and method for rapidly and completely filling containers with toxic liquid material without forming foam within the container or filling apparatus. This object is important, because it is desired to fill the container with liquid and not foam.

A further object of my invention is to provide a reliable apparatus, system, and method for rapidly and completely filling containers with toxic liquid material to a constant filling height irrespective of the container size without utilizing complicated weighing, volumetric measurement, and/or timing techniques.

Still another object of my invention is to provide a reliable apparatus, system, and method for rapidly and completely filling containers with toxic liquid material which prevents overflow of the container; avoids container, work surface, and filling apparatus contamination, and eliminates decontamination washdown procedure.

A still further object of my invention is to provide a reliable apparatus, system, and method for rapidly and completely filling containers with toxic liquid material which eliminates any type of pretreatment of the container to be filled.

Other objects of my invention will be obvious or will appear from the specification hereinafter set forth.

FIG. 1 is a sectional view of my filling head apparatus within the container to be filled.

FIG. 2 is a schematic diagram of my filling system.

FIG. 3 is a view showing a rotatable table for placing containers in a position to be filled by my apparatus.

My invention as shown in FIGS. 1 and 2 will now be described in detail as follows.

Container 2 is moved into the filling position by any conventional means 56 shown in FIG. 3, such as the conventional conveyor belt or rotating tabletop feed such as table 2 in FIG. 1 of U.S. Pat. No. 2,377,796. The movement of containers into filling position as well as all sequencing steps in the filling procedure is controlled by a conventional electronic sequencing unit 22 as shown in FIG. 2. The sequencing unit circuitry comprises a power supply, timing circuits, and control relays such as disclosed in FIGS. 7-9 of U.S. Pat. No. 2,377,796. When container 2 is brought into the filling position as described above, the container closes microswitch 23, which is conventionally electrically connected in series with conventional solenoid 24. Upon closing switch 23, solenoid 24 is activated which in turn activates the conventional four-way valve 25, which may be either an electropneumatic valve or a

hydraulic valve. Activation of valve 25 permits air (THE SOURCE NOT SHOWN IN THE DRAWING) to flow in line 30 and causes my filling apparatus to be lowered by means of cylinder 54 connected to filling head rod 1 into the filling position until needle 12 is located within container 2 and in sealing engagement with the container by means of O-ring 3, as shown in FIG. 1. When the proper filling position is reached microswitch 26 electrically connected in series with valve 25 opens the electrical circuit and stops the filling apparatus in the proper position. Simultaneously with the activation of switch 26, microswitch 27, electrically connected in series with conventional solenoid 28, closes the circuit to solenoid 28 and causes the solenoid to be activated. Solenoid 28, in turn, activates the conventional three-way valve 29 in the manner described above regarding valve 25. Valve 29 can be an electropneumatic or hydraulic valve. Simultaneously with the activation of switch 27, air is evacuated from container 2 by means of a vacuum line (not shown in the drawing) connected to port 4 in the conventional manner. Activation of valve 29 causes air to flow in line 31 (the source of air not shown in the drawing) and to energize spring-loaded cylinder 6 through line 7. Energizing the cylinder causes valve 5 to move upward and permit ball closure 8 housed in chamber 55, to be moved into sealing engagement with O-ring 3 by means of spring activator 18. The timing sequence in panel 22 then activates pump 32 which raises liquid to be filled into container 2 from reservoir 33 through line 34 to inlet 35. The liquid then flows through chambers 36, 37, and 38 into container 2. Foaming within container 2 is avoided by means of the centrifugal force induced to the liquid in chamber 38 by means of helix 11 located within the chamber, which enables the liquid to drain down chamber 38 walls rather than drop straight into the chamber. A further aid in eliminating foaming is the parabolic curvature of the upper surface of point 39 and needle 12, which imparts an umbrella-shaped curtain of liquid with a clear center. The liquid level continues to rise in container 2 until the bottom of point 39 is reached. After reaching point 39, a stream of liquid is pulled up tube 15 of needle 12 by means of vacuum applied to ports 13 and 14 in the conventional manner. Liquid flows from tube 15 into chamber 16 which is provided with baffle 19, the baffle being incorporated to avoid giving false signals to electrodes 17 due to splashing. When the liquid level rises to electrodes 17 in chamber 16, the liquid acting as an electrolyte, an electrical circuit is completed to microswitch 41 which activates solenoid 28 to close valve 29 by means of conventional spring return mechanism 42; the circuit to microswitch 41 being completed through conductors 57 which are connected to electrodes 17 in the conventional manner. Closing of valve 29 interrupts a flow to cylinder 6 which causes valve 5 to close in sealing engagement with chamber 36 by means of O-ring 43 and to interrupt liquid flow to the container. Excess liquid in chambers 36 and 37 is drained back to reservoir 33 by means of outlet 10. Positive drain back from chamber 37 is insured by chamber 37 being installed at an angle of approximately 10° from the horizontal measured in a counterclockwise direction. Valve 5 is designed in a T configuration and fits snugly into chamber 36 as a safety feature to avoid liquid leakage should O-ring seals 43 fail. The filling apparatus is then partially raised, by means of control panel 22, so that point 39 is above the liquid level within the container but still within the container. In such a raised position, excess liquid is drained from tube 15 and chamber 16 by means of vacuum to reservoir 33 through lines 45 and 46. The vacuum system is then shut down, the filling apparatus returned to its starting position, the filled container moved from the filling position to a closed position, and the procedure as described above cyclically repeated. Since filling is accomplished by subjecting the container to vacuum, toxic liquids having a low vapor pressure would partially vaporize and condense at fill opening 44. In order to avoid such condensation, an annular groove 20 is provided in needle housing 47 with sleeve 21 extending from the groove to vacuum port 4. Such means prevents any liquid

vapor extending above groove 20 during the vacuum cycle. Pump 48 is provided to add make-up liquid to the system from a source not shown in the drawing. Pressure within the system is monitored by gauges 49, and liquid amount within the system is monitored by gauge 50. Valves 51 are provided for periodic maintenance, adding make-up liquid, draining liquid from the system, and relieving pressure buildup within the system as required in the conventional manner. All liquid feed lines as required in the conventional manner. All liquid feed lines are conventional flexible tubing such as Tygon. The return of the filling apparatus to its starting position is accomplished by activating spring return mechanism 52 through solenoid 24 which interrupts the airflow through line 30 and exhausts the air through line 53. The conventional timing circuits utilized with my apparatus are correlated to insure proper sequencing of events so that each step is carried out as described above.

It is obvious that other modifications can be made of my invention, and I desire my invention to be limited only by the scope of the appended claims.

I claim:

1. An improved system for filling containers with liquids comprising a reservoir, conduit means connecting said reservoir with a filling means, electronic sequencing control panel, a plurality of valves integral with said conduit means, a plurality of monitoring gauges integral with said conduit means, means to place a container to be filled in a filling position, means to lower said filling means in a filling opening within said container, a plurality of switch means to insure proper positioning of said container and said filling means, to provide sealing engagement between said container and said filling means, vacuum exhaust means to exhaust said container, and means for activating said filling means; the improvement in combination with said system being a filling head comprising a first chamber means integral with and located between an inlet means and a second chamber means, said first chamber means being provided to receive liquid from the reservoir for transfer to the second chamber means during a filling cycle; a third chamber means integral with and located between said first chamber means and an outlet means communicating with said reservoir, said third chamber means being provided to house a sealing means located within said third chamber means and to transfer liquid to the outlet means for transfer to the reservoir during a nonfilling cycle; said sealing means being provided to permit transfer of liquid from the first to the second chamber means and prevent liquid from entering the third chamber means during the filling cycle while allowing communication between the second and third chamber means during the nonfilling cycle to allow for drainage of the second chamber means; valve means located within said first chamber means and connected to a cylinder means, said valve and cylinder means being provided to permit flow of liquid from the inlet means to the first chamber means during the filling cycle; said second chamber means being integral with a fourth chamber means at the extremity of said second chamber means opposite to that which is integral to said first chamber means, said second chamber means being provided to receive liquid from the first chamber means for transfer to the fourth chamber means during the filling cycle and said fourth chamber means being provided to receive liquid from the second chamber means for transfer to the container during the filling cycle; a tubular means located within said fourth chamber means, said tubular means having one extremity terminated in a pointed structure and the second extremity within a fifth chamber means, said tubular means being provided to assist in eliminating foaming action of the liquid on entering the container and to convey a column of liquid to the fifth chamber means; a first baffle means within said fourth chamber means and surrounding said tubular means, said first baffle means being provided to induce centrifugal force action on the liquid to assist in eliminating foaming action of the liquid on entering the container; an electrode means located within said fifth chamber means, said electrode means being

provided to close an electrical circuit which closes the valve means to interrupt the filling cycle and start the nonfilling cycle to return the liquid to the reservoir; and a second baffle means located within said fifth chamber means and interposed between said electrode means and said second tubular extremity, said second baffle means being provided to avoid liquid splash against the electrode and prevent premature closing of the electrical circuit.

2. The system of claim 1 wherein said second chamber means is inclined at an angle of approximately 2° to result in the horizontal surface of the second chamber means joining the vertical surfaces of the first and fourth chamber means at angles of approximately 88° and 92° respectively, the angles being measured in a counterclockwise direction whereby drainage of the second chamber means to the third chamber means during the nonfilling cycle is facilitated.

3. The system of claim 1 wherein said sealing means is a spring-loaded ball seal.

4. The system of claim 1 wherein said valve means has a T configuration and fits snugly within said first chamber means to provide a positive seal.

5. The system of claim 1 wherein said cylinder means is an air-actuated spring-loaded cylinder.

6. The system of claim 1 wherein said pointed structure has an upper surface which is a parabolic curve in configuration.

7. The system of claim 1 wherein said first baffle means is a helix.

8. The system of claim 1 wherein said fifth chamber means is provided with a plurality of vacuum ports located below said second baffle means.

9. The system of claim 1 wherein an annular groove is provided in the outer wall of said fourth chamber means which is adapted to avoid liquid condensation collecting in said filling opening.

10. The system of claim 9 wherein a vacuum port is located above said groove which is adapted to drain off vapor condensation and overflow liquid.

11. The system of claim 10 wherein a sleeve means is provided between said groove and said vacuum port which is adapted to provide a channel for flow of vapor condensation and overflow liquid.

12. An apparatus for filling container with liquids comprising a first chamber means integral with and located between an inlet means and a second chamber means, said first chamber means being provided to receive liquid from a reservoir for transfer to the second chamber means during a filling cycle; a third chamber means integral with and located between said first chamber means and an outlet means communicating with said reservoir, said third chamber means being provided to house a sealing means located within said third chamber means and to transfer liquid to the outlet means for transfer to the reservoir during a nonfilling cycle; said sealing means being provided to permit transfer of liquid from the first to the second chamber means and prevent liquid from entering the third chamber means during the filling cycle while allowing communication between the second and third chamber means during the nonfilling cycle to allow for drainage of the second chamber means; valve means located within said first chamber means and connected to a cylinder means, said valve and cylinder means being provided to permit flow of liquid from the inlet means to the first chamber means during the filling cycle; said second chamber means being integral with a fourth chamber means at the extremity of said second chamber means opposite to that which is integral to said first chamber means, said second chamber means being provided to receive liquid from the first chamber means for transfer to the fourth chamber means during the filling cycle and said fourth chamber means being provided to receive liquid from the second chamber means for transfer to a container during the filling cycle; a tubular means located within said fourth chamber means, said tubular means having one extremity terminated in a pointed structure and the second extremity within a fifth chamber means, said tubular means being provided to assist in eliminating foaming action of the liquid on entering the container and to convey a column of liquid to the fifth chamber means; a first baffle means within said fourth chamber means and surrounding said tubular means, said first baffle means being provided to induce centrifugal force action on the liquid to assist in eliminating foaming action of the liquid on entering the container; an electrode means located within said fifth chamber means, said electrode means being

provided to close an electrical circuit which closes the valve means to interrupt the filling cycle and start the nonfilling cycle to return the liquid to the reservoir; and a second baffle means located within said fifth chamber means and interposed between said electrode means and said second tubular extremity, said second baffle means being provided to avoid liquid splash against the electrode and prevent premature closing of the electrical circuit.

13. The system of claim 12 wherein said second chamber means is inclined at an angle of approximately 2° to result in the horizontal surface of the second chamber means joining the vertical surfaces of the first and fourth chamber means at angles of approximately 88° and 92° respectively, the angles being measured in a counterclockwise direction whereby drainage of the second chamber means to the third chamber means during the nonfilling cycle is facilitated.

14. The system of claim 13 wherein said sealing means is a spring-loaded ball seal.

15. The system of claim 14 wherein said valve means has a T configuration and fits snugly within said first chamber means to provide a positive seal.

16. The system of claim 15 wherein said cylinder means is an air-actuated spring-loaded cylinder.

17. The system of claim 16 wherein said pointed structure has an upper surface which is a parabolic curve in configuration.

18. The system of claim 17 wherein said first baffle means is a helix.

19. The system of claim 18 wherein said fifth chamber means is provided with a plurality of vacuum ports located below said second baffle means.

20. The system of claim 19 wherein an annular groove is provided in the outer wall of said fourth chamber means which is adapted to avoid liquid condensation collecting in said filling opening.

within a fifth chamber means, said tubular means being provided to assist in eliminating foaming action of the liquid on entering the container and to convey a column of liquid to the fifth chamber means; a first baffle means within said fourth chamber means and surrounding said tubular means, said first baffle means being provided to induce centrifugal force action on the liquid to assist in eliminating foaming action of the liquid on entering the container; an electrode means located within said fifth chamber means, said electrode means being provided to close an electrical circuit which closes the valve means to interrupt the filling cycle and start the nonfilling cycle to return the liquid to the reservoir; and a second baffle means located within said fifth chamber means and interposed between said electrode means and said second tubular extremity, said second baffle means being provided to avoid liquid splash against the electrode and prevent premature closing of the electrical circuit.

13. The apparatus of claim 12 wherein said second chamber means is inclined at an angle of approximately 2° to result in the horizontal surface of the second chamber means joining the vertical surfaces of the first and fourth chamber means at angles of approximately 88° and 92° respectively, the angles being measured in a counterclockwise direction whereby drainage of the second chamber means to the third chamber means during the nonfilling cycle is facilitated.

14. The apparatus of claim 12 wherein said sealing means is a spring-loaded ball seal.

15. The apparatus of claim 12 wherein said valve has a T configuration and fits snugly within said first chamber means to provide a positive seal.

16. The apparatus of claim 12 wherein said cylinder means is an air-actuated spring-loaded cylinder.

17. The apparatus of claim 12 wherein said pointed structure has an upper surface which is a parabolic curve in configuration.

18. The apparatus of claim 12 wherein said first baffle is a helix.

19. The apparatus of claim 12 wherein the fifth chamber means provided with a plurality of vacuum ports located below said second baffle means.

20. The apparatus of claim 12 wherein an annular groove is provided in the outer wall of said fourth chamber means which

is adapted to avoid liquid condensation collecting in said filling opening.

21. The apparatus of claim 20 wherein a vacuum port is located above said groove which is adapted to drain off vapor condensation and overflow liquid.

22. The apparatus of claim 21 wherein a sleeve means is provided between said groove and said vacuum port which is adapted to provide a channel for flow of vapor condensation and overflow liquid.

- 10 23. A process for introducing an electrically conductive liquid into a container comprising the steps of sequentially moving a container having a filling opening into a filling position, lowering a filling head into seating engagement within said filling opening by means of an air-actuated cylinder 15 preparatory to filling the container, exhausting the air from said container by vacuum means to reduce the pressure on the liquid, closing a switch means to activate an air supply means which causes activation of a spring-loaded cylinder means, activating the spring-loaded cylinder means by said air supply 20 means to open a valve means, opening the valve means by said spring-loaded cylinder means to permit liquid to flow from an inlet means through a plurality of chamber means to fill the container, closing an outlet means communicating with the reservoir simultaneously with the valve means opening to 25 avoid return of the liquid to a reservoir means and permit flow of the liquid through the plurality of chamber means to the container, pumping liquid from the reservoir means through said inlet and plurality of chamber means into said container simultaneously with the valve means opening and the outlet 30 means closing, withdrawing a column of liquid from said container into a tubular means after the container has been filled to predetermined level, introducing liquid from said column into a chamber containing an electrode means after the tubular means has been filled, activating said electrode means by said liquid contacting the electrode means, closing an electrical circuit means by said contact of the electrode with the liquid which interrupts the flow of liquid to the container by the electrical circuit causing the air supply to be interrupted which closes the valve means and opens the outlet means, 35 removing said container from the filling position after the liquid retained within said filling head has drained to the reservoir means, and cyclically repeating the process.
